PRESSURE OPERATED SWITCH

Harry Frohman, Charlotte, N. C., assignor to
 Brown Grease Gun Corporation, Charlotte,
 N. C., a corporation of North Carolina

Application April 13, 1937, Serial No. 136,633

3 Claims. (Cl. 200—82)

This invention relates to a pressure operated switch which is adapted to be inserted in any fluid pressure line for automatically controlling a motor which in turn, creates a pressure in the line. In fluid pressure lines it is very often desirable to maintain the pressure within predetermined limits. This is especially true in case of a grease dispensing apparatus where measured quantities of grease are delivered to a bearing 10 such as a shackle in a motor vehicle and a high pressure is essential in order to effect the delivery.

It is therefore, an object of this invention to provide a fluid pressure operated switch for controlling a motor circuit which in turn, drives a pump for maintaining a pressure in a line.

It is a further object of this invention to provide a switch of the class described with means for varying the point at which said switch will make or break contact. By providing this adjusting means, it is possible to select a range of pressures within which the switch is adapted to operate thereby making the switch capable of being used under varied conditions.

Some of the objects of the invention having been stated, other objects will appear when taken in connection with the accompanying drawing, in which:

Figure 1 is a perspective view showing one side of the invention;

Figure 2 is a perspective view of the invention looking at a different angle from that in Figure 1;

Figure 3 is an isometric view with portions thereof broken away showing the structure enclosed in the housing;

Figure 4 is an elevation of the invention showing the switch operating mechanism disposed therein in section;

Figure 5 is a sectional detail view of the contact washer on insulation rod.

Referring more specifically to the drawing, the numeral 10 indicates a suitable housing in which a fluid pressure operated switch is adapted to be mounted. This housing has a cover plate 11 removably secured thereon by any suitable means such as set screws 12. Suitable holes are provided in upwardly projecting lugs 10a which are integral with the housing 10 to provide means for securing the housing to some object.

A pair of wires 13 and 14 lead into the housing 10 and are connected to terminals 15 and 16 respectively, said terminals being threadably secured in insulation cylinder block 17. This block 17 has one end thereof secured in T-shaped member 18, which member is threadably secured around the intermediate portion of longitudinally

disposed rod 19. This rod has its ends rotatably mounted in the housing 10. In order to provide means for moving the T-shaped member 18 and its associated cylinder 17 longitudinally of the housing 10 a knurled knob 20 is disposed on one end of the rod and on the exterior of the housing. This knob may be turned in the desired direction to cause the members 17 and 18 to move back and forth within the housing 10, thereby determining the point at which the circuit will be made or broken. A conductive washer 25 is loosely secured on one end of insulation rod 26, both the rod and the bar 25 being slidably mounted in bore 17a within cylinder 17. The washer 25 is held on rod 26 by screw 25a as shown in Figure 5, thus allowing contact with both contacts 15 and 16, even though they may be of different lengths. The rod 26 is also supported by a plug 27 which is secured in the end of cylinder 17 by means such as set screw 28. In the present position of bar 25, no contact is being made between terminals 15 and 16 since a sufficient pressure has been generated to cause the bar to be removed to the left and away from these terminals.

The mechanism for actuating the rod 26 and bar 25 comprises a forked bar 30 which has its upper end resting astride the end of rod 26 and has its lower end secured around pressure rod 31 between collars 32 and 33. In order to hold the upper forked end of bar 30 intact with the rod 26 as rod 31 moves to the left a suitable washer 34 and a cotter pin 35 has been provided on the end of rod 26. The switch bar 25 and rod 26 are held in contact with the terminals 15 and 16 by means of a compression spring 36 which is disposed around rod 26 and has one end thereof engaging the bar 25 and its other end engaging the plug 27. In other words, this spring acts against the pressure and when the circuit is broken between the terminals 15 and 16.

The rod 31 has the left-hand end thereof slidably mounted in the end of casing 10. A second compression spring 37 is mounted around rod 31 between the casing 10 and the collar 32, which spring normally tends to force the rod 31 to the right in Figure 4. The right-hand end of the rod 31 is slidably mounted in cylinder 38 which cylinder has a bore 39 therein. The bore 39 has communicating therewith a restricted bore in which is slidably mounted pin 40 which pin is integral with the right-hand end of rod 31. The restricted bore in which the pin 40 is mounted has a second bore communicating therewith in which a packing gland 41 is mounted. This gland has adjacent its right-hand end a slidably

mounted sleeve 42 which houses the extreme right-hand portion of pin 40. The cylinder 38 is threadably secured in the end of housing 10 and has secured in the end thereof a pipe fitting 43 to which a pressure line is secured. When the pressure is applied to this line, the pin 40 and its associated piston rod 31 is moved to the left in Figure 4, thereby causing the member 30 to move the rod 26 and the contact bar 25 to the left and break the circuit which will, in turn, stop the motor.

When the pressure has been relieved the rod 31 and its associated parts will move back to the right which will allow the spring in cylinder 36 to move the contact bar 25 into contact with terminals 15 and 16 to start the motor again.

It is seen that the right-hand end of pin 40 (Fig. 4) is the only area upon which the pressure is applied; consequently, the spring 37 will not have to be of very great strength since the area upon which the pressure acts is very small. Furthermore, since the sleeve 42 is slidably mounted in the right-hand end of the member 38 and contacts the packing gland 41, this gland 25 will naturally be compressed around the pin 40 to prevent any leakage of the pressure.

The T-shaped member 17 has secured thereto an L-shaped indicator 45 which penetrates a slot 46 in the housing 10. The upper end of the indicator is pointed and disposed over a scale 47 on plate 48. By turning the nut 20 and its associated parts, this indicator will be moved back and forth over the scale 47 to indicate the point at which the switch will be disconnected.

It is evident that the location of the cylinder 19 relative to pressure cylinder 38 determines the amount of pressure necessary to be set up within the cylinder 38 to cause the contact to be broken. In other words, the nearer the cylinder 17 is disposed to the left-hand end of housing 10, the more will be the pressure necessary to compress spring 37 so that the contact 35 will be moved away from terminals 15 and 16. In order to limit the amount that the cylinder 17 may be moved to the right in the housing 10, a suitable set screw 49 is provided which acts as an adjustable stop for contacting the end of the cylinder.

It is therefore seen that I have provided a fluid pressure operated switch for controlling the pressure between predetermined limits in a pressure line with means for varying the point at which the switch will be operated. In this case the limits between which the built up pressure can be relieved from the pressure line without again making contact and starting the motor is necessarily small, but there is a short pressure range after the switch has been disconnected in which pressure may be used without allowing the switch to move back again to the connected position. This pressure range is produced by the momentum of the motor which creates a pressure within the pressure lines. At the time of the disconnecting of the bar 25 from the contacts 15 and 16 the contact bar is moved an appreciable distance away from the terminals which distance is again traversed by the bar 25 as the pressure is relieved before contact is made. This short distance, while only a matter of a fraction

of an inch in a switch used in an ordinary grease dispensing apparatus, represents the range of pressure which may be utilized without again starting the motor. It is very undesirable to have a wide pressure range, especially where a maximum pressure is desired to be available at all times.

It is evident that after pressure has been built up to open the switch that the pressure generated by the motor has not all reached the piston 40 and thus after the circuit is broken this belated pressure will open the switch to a greater degree and thus provide a working range.

In the drawing and specification there has been set forth a preferred embodiment of the invention, and although specific terms are employed, they are used in a generic and descriptive sense only, and not for purposes of limitation, the scope of the invention being set forth in the appended claims.

I claim:

1. A pressure operated electrical switch comprising a casing, a cylinder of insulating material disposed in said casing, a pair of contacts in the base of said cylinder, a rod of insulating material disposed in said cylinder and having a metallic disk on one end thereof adapted to contact said pair of contacts, a threaded rod disposed in said casing, a support for the cylinder threadedly mounted on said threaded rod, a pressure line leading into said casing, a piston disposed in said pressure line, a compression spring normally forcing said piston against the pressure in said pressure line, a projection carried by said piston having a forked end disposed around said insulating rod, means on the insulating rod adapted to be engaged by said projection to move the disk on the rod out of contact with said pair of contacts when a predetermined pressure has been created in the pressure line. 40

2. A pressure operated switch comprising a casing, a threaded rod disposed in said casing, a switch threadably mounted on said threaded rod, a pressure line leading to said casing, a piston in said pressure line and extending into said casing, means on the piston for engaging said switch and opening the same upon a predetermined high pressure being present in the pressure line, compression means tending to normally close said switch, and spring means for moving the piston 50 to allow the compression means to close said switch upon a predetermined low pressure being reached in the pressure line.

3. A pressure operated switch comprising a casing, a rod disposed in said casing, a switch 55 adjustably mounted on said rod, a pressure line leading to said casing, a piston in said pressure line and extending into said casing, means on the piston for engaging said switch and opening the same upon a predetermined high pressure 60 being present in the pressure line, compression means tending normally to close said switch, and spring means for moving the piston to allow the compression means to close said switch upon a predetermined low pressure being reached in the 65 pressure line.

HARRY FROHMAN.
